(57) **CLAIM**

The ornamental design for a handle mount, as shown and described.

DESCRIPTION

FIG. 1 is a front plan view of a handle mount incorporating my new design, shown in combination with the environmental structure of a vibratory screed;

FIG. 2 is perspective view of the handle mount of FIG. 1, viewed from in front of, below, and from the left side of the handle mount;

FIG. 3 is a front elevation view thereof;

FIG. 4 is a top plan view thereof;

FIG. 5 is a right-side elevation view thereof;

FIG. 6 is a left-side elevation view thereof;

FIG. 7 is a bottom plan view thereof; and,

FIG. 8 is a rear elevation view thereof.

The broken lines in FIGS. 1-8 are for illustrative purposes only and form no part of the claimed design.
